UNITED STATES PATENT OFFICE.

ADELBERT O. BLETHEN AND WILLIAM J. EVANS, OF MINNEAPOLIS,
MINNESOTA.

DESIGN FOR A BICYCLE-RACK.

SPECIFICATION forming part of Design No. 27,662, dated September 21, 1897.

Application filed August 14, 1897. Serial No. 648,329. Term of patent 3¹ years.

To all whom it may concern:

Be it known that we, ADELBERT O. BLETHEN and WILLIAM J. EVANS, citizens of the United States, residing at Minneapolis, in the county 5 of Hennepin and State of Minnesota, have invented and produced a new and original Design for a Bicycle-Rack, of which the following is a specification, reference being had to the accompanying drawing, forming a part 10 thereof, in which is represented a perspective view of a bicycle-rack embodying the features of the design.

The leading feature of the design consists in the representation A of a bottle, demijohn, 15 or similar receptacle, in the lower portion of the body of which elongated openings B are made.

Another feature of the invention consists in providing for the receptacle-body A a base

C, which comprises a horizontal member and 20 side members c, extending upwardly therefrom and apparently connecting with the receptacle-figure A.

Another feature of the invention consists in forming on the receptacle-figure A panels 25 D, which may resemble characteristic panels or labels upon any predetermined receptacle from which in a manner the receptacle A is patterned.

We claim—

30 The design for the bicycle-rack herein shown and described.

ADELBERT O. BLETHEN.
WILLIAM J. EVANS.
